(57) **CLAIM**

The ornamental design for a pager, as shown and described.

DESCRIPTION

FIG. 1 is a perspective view of a pager in accordance with my design;

FIG. 2 is a front view thereof;

FIG. 3 is a rear view thereof;

FIG. 4 is a left side view thereof;

FIG. 5 is a right side view thereof;

FIG. 6 is a top plan view; and,

FIG. 7 is a bottom plan view.

The broken line showing the clip in FIGS. 1-7 is included for the purpose of illustrating environmental structure only and forms no part of the claimed design.

1 Claim, 2 Drawing Sheets
